HAND DRILL

James H. Godfrey, Berlin, and Richard H. Russell and
Charles R. Tyke, New Britain, Conn., assignors to The
Stanley Works, New Britain, Conn., a corporation of
Connecticut

Filed Oct. 12, 1962, Ser. No. 72,085

Term of patent 14 years

(Cl. D54—14)

FIG. 1 is a perspective view of a hand drill showing our new design;

FIG. 2 is a rear elevational view;

FIG. 3 is a front elevational view;

FIG. 4 is a top plan view;

FIG. 5 is a bottom plan view thereof; and

FIG. 6 is a perspective view of the hand drill with the rear and upper handles omitted.

The dominant features of my design reside in the full line portions of the drawing. The side of the hand drill not shown is the same as the side shown.

We claim:
The ornamental design for a hand drill, as shown and described.
